Primary Examiner — Robert M Spear*Assistant Examiner* — Darcey E Heflin(74) *Attorney, Agent, or Firm* — Harness, Dickey & Pierce, P.L.C.(57) **CLAIM**

The ornamental design for a heart-shaped stringed instrument, as shown and described.

DESCRIPTION

FIG. 1 is a front perspective view of heart-shaped stringed instrument;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a back elevational view thereof.

The broken lines immediately adjacent shaded surfaces depict claim boundaries. All other broken lines depict portions of the heart-shaped stringed instrument that form no part of the claim.

1 Claim, 3 Drawing Sheets(56)
